BURETTE UNIT FOR THE ELUTION OF CHEMICAL SUBSTANCES FROM PAPER

Joseph Kopp, 70—13 35th Road, Jackson Heights, N.Y.

Filed Mar. 26, 1962, Ser. No. 69,498

Term of patent 14 years

(Cl. D16—1)

FIG.1

FIG.3

FIG.2

FIGURE 1 is a perspective view of a burette unit for the elution of chemical substances from paper, showing my new design.

FIGURE 2 is a top plan view thereof.

FIGURE 3 is a transverse section thereof, with the lower internal portion shown in elevation. The portions shown in dotted lines are for purposes of illustration only. The side not shown is substantially the same in appearance as the side shown.

I claim:

The ornamental design for a burette unit for the elu-

tion of chemical substances from paper, as shown and described.
